(57) **CLAIM**

The ornamental design for a lighting fixture, as shown and described.

DESCRIPTION

This application contains subject matter which is related to the subject matter of co-filed U.S. Design patent application Ser. No. 29/456,673, entitled "Lighting Fixture" by Doyle Crosby, which application is hereby incorporated in its entirety herein by reference.

FIG. 1 is a front elevation view of a lighting fixture in accordance with the new design;

FIG. 2 is a rear elevational view thereof;

FIG. 3 is a right side elevational view thereof; and,

FIG. 4 is a left side elevational view thereof.

The broken lines in the figures are for illustration purposes only and form no part of the claimed invention.
